CLAIM

The ornamental design for a sliding and rotating ball, as shown and described.

DESCRIPTION

FIG. 1 is an upper front perspective view of the sliding and rotating ball showing my new design.

FIG. 2 is a lower front perspective view thereof.

FIG. 3 is a front side view thereof.

FIG. 4 is a rear side view thereof.

FIG. 5 is a right side view thereof.

FIG. 6 is a left side view thereof.

FIG. 7 is a top view thereof; and,

FIG. 8 is a bottom view thereof.
